UNITED STATES PATENT OFFICE

JEAN JOSEPH VAN DEN BOSSCHE, OF ENGHIEIEN, BELGIUM

STEAM TURBINE

Application filed August 27, 1925, Serial No. 52,936, and in Germany August 28, 1924.

My invention relates to a multi-stage turbine and provides an improved structure which is based on the fact that heat can be directly transformed into kinetic energy. 5 In the turbine according to my present invention the temperature of the flowing steam is decreased not solely by expansion but by considerably extending the way the steam is compelled to take and by subjecting the 10 steam to the action of centrifugal force. In the practical embodiment of my invention, which will be described hereinafter, the flowing steam is conducted alternately along a radial outward and a radial inward path and 15 during each reversal is subjected to the influence of centrifugal force. It is by these combined means that almost no steam leaves the turbine at the exit end, but all steam consumed is condensed into water which is used 20 as a sealing agent taking a counter flow to the direction of the steam and being collected and tapped at the steam entrance end of the turbine. The immediate result of 25 my present method of transforming the heat of the steam directly into kinetic energy is the fact that there are no other losses of heat than those which occur accidentally by radiation, conductibility, and leakages which, however, can be reduced as much as 30 possible.

My invention is illustrated diagrammatically and by way of an example in the accompanying drawing in which Figure 1 is an axial section through a vertical 35 two-stage steam turbine devised according to this invention; Figure 2 shows two horizontal sections through one of the rotors, the lefthand half of the figure being a section in the plane A—B of Fig. 1, and the 40 righthand half a section in the plane C—D of Fig. 1; and Figure 3 is a horizontal section in the plane E—F of Fig. 1.

Referring to the drawing, *a* denotes a vertical shaft to which are keyed a number of 45 disks of which two, *b* and *c*, are shown. These disks are bladed on both sides. *d* is the casing, *n* are annular partition walls bearing curved guide blades *e* and *f* on their upper faces (Fig. 3) and in opposition to 50 blades *h* of the wheel disks *c* and *b*. I pre-

fer to have these blades *h* curved as shown in the right hand half of Fig. 2. The compartments formed around each set of bladed disks or wheels leave at the circumference of the latter chambers *i* in which the stem is subjected to the action of the centrifugal force. Between two adjacent wheels, inner annular steam chambers are formed by openings in the partition walls *n*. The path followed by the steam entering at the inlet branch *k* to the outlet branch *o*, as indicated by arrows *z*. The steam flows radially outwards when passing along the blades *h* of the first and second stage, and radially inwards when passing along the turbine blades *g*. The steam is thereby compelled to cover a long way and to remain a long time in the turbine under the action of centrifugal force in conjunction with the heat depriving influence of the casing walls of the turbine, and imparts to the blades *h* and *g* a part of the kinetic energy released by the decrease of its temperature. The temperature and pressure of the steam will drop from one stage to another. In Fig. 2, *m* denotes the 55 passages between the turbine blades *g* which can be curved, too. Within these passages the kinetic energy of the steam molecules flowing towards the inner steam chambers is taken up by the blades *g*.

The condensed water which accumulates in the turbine as a result of the direct transformation of heat into motive power is being thrown radially outwards against the circumferential walls of the chambers *i* and then 60 passes between the guide blades *e* and *f* to the center openings of the walls *n*. Finally, the condensed water collects in the lowermost part of the casing *d* from where it may be returned to the boiler through passages *p*, *q*, *r*. As the condensed water is moving in 65 opposition to the flow of the steam within the vertical turbine, it serves also as a sealing agent and thus prevents leakages of steam.

As the steam is to be condensed above boiling point in the turbine, no steam-jacket or the like is required for the casing of the same.

The turbine may be worked with ordinary wet steam or with dry steam or with superheated steam, and it may be live steam, ex- 100

haust-steam, or steam given off by boiling water within the turbine. If a part of the steam remains uncondensed it escapes through the branch *o* and may either be 5 sucked off by means of an ice-cooled condensing pot or be conducted back to the boiler by means of a cooled compressor or a so-called extractor. A part of the water of condensation escaping through the passages *p* may be used as sealing means in the labyrinth packing *s* from which it escapes 10 through the orifices *r*.

From the above it may be seen that the 15 turbine is intended to carry into practice a method for converting steam into motive power in such a manner that the amount of heat contained in the steam is converted into kinetic energy without any rest. The condensed water is flowing through the turbine 20 in a direction opposite to that of the steam so that a certain counter-current is produced and maintained; in other words, the steam and the condensed water penetrate one another whereby the condensed water is heated 25 nearly to boiler-temperature, in consequence whereof this water can be used very economically as boiler feed-water.

I wish it to be understood that the 30 improved turbine described in the preceding paragraphs may be built also as a turbine with horizontal shaft.

My improved steam-turbine may be used 35 in connection with industrial plants of any kind, as well as for driving ships, and it can be used also in connection with vehicles of 40 any kind, especially motor-vehicles, turbine-locomotives, and the like, and I deem it capable for use also in connection with air-craft where boilers with instantaneous steam-generation are employed, as has been proposed 45 and is intended.

I claim:

1. In a turbine, the combination of a casing 50 having an inlet and an outlet for the motive fluid, a shaft, turbine wheels fixedly mounted thereon, each turbine wheel consisting of a disk and radial blades on both sides of said disk and extending over its entire surface, radially extending partition 55 walls within said casing, whereby a compartment is formed for each of said double bladed turbine wheels, said compartments being of the same size throughout said casing and having equally sized annular passages around each turbine wheel, said partition walls leaving central steam passages of the 60 same size throughout said casing.

2. In a turbine, the combination of a casing 65 having an inlet and an outlet for the motive fluid, a shaft, turbine wheels fixedly mounted thereon, each turbine wheel consisting of a disk and radial blades on both sides of said disk and extending over its entire surface, radially extending partition 70 walls within said casing, whereby a compartment is formed for each of said double bladed turbine wheels, said compartments being of the same size throughout said casing and leaving equally sized annular passages around each turbine wheel, said partition walls leaving central steam passages of the same size throughout said casing, and stationary guide blades upon said partition walls and opposite those of said radial 75 blades through which the steam flows radially outwards.

3. In a turbine, the combination of a casing 80 having an inlet and an outlet for the motive fluid, a vertically arranged shaft, turbine wheels fixedly mounted thereon, each turbine wheel consisting of a disk and radial blades on both sides of said disk and extending over its entire surface, a vertically extending casing, radially extending partition walls within said casing, whereby 85 a compartment is formed for each of said double bladed turbine wheels, said compartments being of the same size throughout said casing and leaving equally sized passages around each turbine wheel, said partition walls leaving central steam passages of the same size throughout said casing, at the base of said casing a collecting trough 90 for condensed water descending in opposite direction to the flowing steam, and discharge openings within said collecting trough.

In testimony whereof I affix my signature.
JEAN JOSEPH VAN DEN BOSSCHE.
